ELECTRIC SEMIAUTOMATIC DOOR
OPERATOR

Kenneth L. Mosher, Riceville, Iowa

Application September 26, 1947, Serial No. 776,181

3 Claims. (Cl. 160—193)

1

This invention relates to doors and more particularly to an electric operator for doors of a hangar or the like.

It is an object of this invention to provide an improved door structure for large buildings such as hangars, which have doors extending substantially across the length of one end thereof.

Another object of this invention is to provide an improved door and door operator for a structure of this kind in which the weight of the door is substantially supported on a door operating shaft, and the door sections which are hingedly connected together are so constructed and arranged that the sections provide a reinforcement for each other in their vertical folded position, thereby providing a solid structure for resisting the forces of wind and the like.

A further object of this invention is to provide a door and door operator of this kind which is relatively economical to construct and which is adapted for proper operation in high winds. The construction and arrangement of the door and the operating means therefor is such that nearly all the thrust on the end of the building is eliminated and absorbed by the cable control system.

A still further object of this invention is to provide an improved locking member for locking the upper and lower door sections in aligned or closed position. The locking member is removably supported on the hinge between the two door sections and may be completely removed for operating the doors to their open position. The locking member substantially reinforces the joint between the upper and lower sections in their aligned or closed position and secures them against inadvertent swinging movement about the hinges therebetween.

With the above and other objects in view, my invention consists in the arrangement, combination and details of construction disclosed in the drawings and specification, and then more particularly pointed out in the appended claims.

In the drawings,

Figure 1 is a front elevation of a door and door operator constructed according to an embodiment of this invention,

Figure 2 is a vertical section taken on the line 2—2 of Figure 1 showing the door in the lowered position,

Figure 3 is a section taken substantially on the line 2—2 of Figure 1 showing the door in the raised position,

Figure 4 is a perspective view of the door lock in the raised or open position, and

2

Figure 5 is a perspective view of the door lock in its closed or locked position.

Referring to the drawings, the numeral 10 designates generally a large structure such as a hangar or the like, having a door 11 at one end thereof which is adapted to be raised and folded vertically.

In the use of doors of this type much difficulty has been experienced in properly supporting the doors so that the doors will operate efficiently in all weather conditions both in the opening and closing thereof.

I have provided a door 11 formed of an upper section 12 and a lower section 14 hingedly connected together and to the structure 10 for folding vertically about horizontal hinges. The structure 10 embodies a door frame including a header section disposed between the sides of the door frame contiguous to the upper end thereof and secured thereto. The door section 12 is hingedly connected to the transverse beam 15 of the structure 10 by a plurality of horizontally spaced apart hinges 16, the hinges being disposed exteriorly of the structure 10.

The lower section 14 of the door 11 is hingedly connected at its upper end to the lower end of the door section 11 by a plurality of hinges 17 having horizontal pintles contained thereon, the pintles being disposed exteriorly of the structure 10. The lower door section 14 may be wider than the upper section 12 to suitably seal the opening in the end of the structure 10.

In its lower or closed position, the door 11 is adapted to completely seal the opening in the structure and the sections 12 and 14 are so arranged that the lower section 14 will move outwardly upon the initial movement thereof so that the door 11 may be folded vertically to completely open the structure 10.

I have provided an electric operating means for actuating the door 11 which may be controlled selectively by an operator. The door control means comprises a drive shaft 18 rotatably supported on bearings 19 on the structure 10 immediately above the upper end of the upper door section 12.

A motor 20 is provided for rotating the shaft 18 and is connected to the shaft by a belt 21 trained about a pulley 22 fixed on the motor shaft and a pulley 24 fixed on a shaft extending from a reduction gear box 25. The power shaft 18 is operatively connected to the reduction gear box 25 for rotation by the motor 20. A switch 26 is fixed on one of the side members of the structure

10 where it may be controlled by an operator and is connected to the motor 20 by wires 21.

A pair of pulleys 28 are fixed on the shaft 18 near the opposite ends thereof. A flexible cable or chain 29 is fixed to the pulley 28 at its upper end and is connected to the lower edge of the lower door section 14 by a pair of downwardly diverging flexible sections 30.

The flexible member 29 is connected to the pulley 28 in such a manner that the cable 29 leaves the pulley 28 rearwardly thereof and extends downwardly to the lower edge of the door section 14.

A pair of second pulleys 31 are fixed on the shaft 18 between the larger pulleys 28 and are provided for connection to an operation of the upper door section 12. A flexible member as a cable or chain 32 is trained about the pulley 31 in such a manner that the cable 32 leaves the pulley 31 forwardly thereof extending upwardly exactly opposite from the engagement of the flexible member 29 with the pulley 28.

An idle pulley 34 is rotatably carried in bearings 35 by the structure above the driving shaft 18. A pulley 34 is disposed above each of the smaller pulleys 31. The flexible member 32 extends upwardly about the pulley 34 where it extends downwardly on the front side of the door 11 for engagement with the lower edge of the upper door section 12.

A pair of downwardly and outwardly divergent flexible members 36 connect the lower end of the cable 32 to the lower end of the door section 12. Suitable means may be provided for stopping the action of the motor and rotation of the shaft 18 in the extreme limits of the door 11 in its raised or lowered position. For locking the door sections 12 and 14 in their aligned position when they are closed, I have provided an improved locking member 40 which may be removably engaged with the door sections 12 and 14 about the hinge 17 thereof.

The locking member 40 is particularly provided for rigidly securing the hinged door sections in their closed positions to prevent the flexing or movement of the sections about the hinges 17 due to wind pressure or other sources which would cause the lower section 14 to swing relative to the upper section 12.

The hinges 17 are formed with hinged leaves 41 and 42 secured on the door sections 12 and 14 respectively. A pintle or hinge pin 44 engages through the barrel 45 of the hinge and extends outwardly a short distance from the side edges thereof. A screw or adjusting bolt 46 is carried by each outer end of the bar 55 for engagement with the leaves 41 and 42. The locking member 40 is formed of a pair of parallel spaced apart hook members 47 connected together at one end, by a pin 48.

The lower end of the hook members 47 is provided with a reverted hook 49 having a bill 50 thereon for engagement about the extended ends of the pintle 44. A lever 51 is rockably supported on the pin 48 between the hook members 47. The lever 51 is formed of an elongated arm 52 and an end arm 54 extends upwardly from one end of the arm 52 at an acute angle thereto or at an angle slightly less than 90°. A locking bar 55 is rockably carried by the lever 51 at the point where the arms 52 and 54 are joined together.

A hinge pin 56 engages through the lever 51 and locking bar 55 intermediate the length thereof. The lower ends of the adjustment bolts 46 on the locking bar 55 are adapted to engage the upper surface of the opposite leaves 41 and 42 for

locking the door sections 12 and 14 in aligned position.

The locking member 40 is removably engaged with the pintle 44 so that it may be removed when it is desired to raise the door 11. In the use and operation of the locking member 40, the hooks 49 are engaged with the extended ends of the pintle 44 with the lever 51 in a raised position as indicated in Figure 4.

10 The lever 51 is then rocked downwardly about the pin 48 until the leaves 12 and 14 are securely engaged with the lower ends of the bolts 46. The arm 54 of the lever 51 is rocked to the right side of the members 47 as seen in Figure 5 for biasing 15 the lever 51 and arm 52 downwardly to the locked position.

A horizontal stop 57 is carried by the free end of the arm 52 transversely thereof and is provided for engagement with the upper side of the locked 20 bar 55. In this locked position of the member 40, the arm 52 is disposed substantially parallel to and adjacent the locking bar 55 with the acute 25 upwardly extending arm 54 disposed in a downwardly and outwardly related position relative to the hook members 47 and the hinge pin 48.

In this manner any force on the door sections 12 and 14 would tend to rock the lever 51 further about the hinge 48 to an increasingly locked position while this lever 51 is restrained against further rocking movement by engagement of the stop 30 bar 57 with the upper side of the locking bar 55.

In order to provide for the accurate fitting of the locking member 40 with the hinge 17, the bolts 46 are threadedly engaged in the locking bar 35 55 for adjustment relative thereto. Lock nuts 58 are provided on the bolts 46 for securing the bolts in selected adjusted position.

The locking member 40 must be completely 40 removed for operating the doors 12 and 14 to a raised position and the member 40 may be secured to one of the door sections by a flexible supporting member (not shown in the drawings) to restrain the locking member 40 from dislocation relative to the hinge 17.

45 I do not mean to confine myself to the exact details of construction herein disclosed but claim all variations falling within the purview of the appended claims.

Having thus described my invention, what I 50 claim is:

1. In a folding door for support within a door frame, a vertically disposed header section adapted to be secured between the sides of said door frame contiguous to the upper end thereof, a 55 first vertically disposed door section positioned in end to end relation with respect to the lower end of said header section and having one end pivotally connected to the latter on an axis transverse of and exteriorly of said header section for swinging 60 movement toward and away from the exterior face of said header section, a second vertically disposed door section positioned in end to end relation with respect to the other end of said first door section and having one end pivotally connected to the latter on an axis transverse of and 65 exteriorly of said first door section for swinging movement toward and away from the interior face of said first door section, a shaft arranged in spaced parallel relation above said transverse 70 axes and mounted on said header section for rotary movement, a pulley carried on said shaft, flexible means having one end trained about said pulley in one direction and secured thereto and having its other end secured to the other end of 75 said second door section, another pulley spaced

from said first named pulley and secured to said shaft, another flexible means having one end trained about said last named pulley in a direction opposite to said first named flexible means and secured to said last named pulley, said last named flexible means extending through said header section and having its other end secured to said first door section, and power means operatively connected to said shaft for effecting the rotary movement of the latter.

2. In a folding door for support within a door frame, a vertically disposed header section adapted to be secured between the sides of said door frame contiguous to the upper end thereof, a first vertically disposed door section positioned in end to end relation with respect to the lower end of said header section and having one end pivotally connected to the latter on an axis transverse of and exteriorly of said header section for swinging movement toward and away from the exterior face of said header section, a second vertically disposed door section positioned in end to end relation with respect to the other end of said first door section and having one end pivotally connected to the latter on an axis transverse of and interiorly of said first door section for swinging movement toward and away from the interior face of said first door section, a shaft arranged in spaced parallel relation above said transverse axes and mounted on said header section for rotary movement, a pulley carried on said shaft, flexible means having one end trained about said pulley in one direction and secured thereto and having its other end secured to the other end of said second door section, another pulley spaced from said first named pulley and secured to said shaft, another flexible means having one end trained about said last named pulley in a direction opposite to said first named flexible means and secured to said last named pulley, said last named flexible means extending through said header section and having its other end secured to said first door section, power means operatively connected to said shaft for effecting the rotary movement of the latter, and switch means disposed remote from said power means and operatively connected to the latter for selectively effecting the rotary movement of said shaft.

3. In a folding door for support within a door frame, a vertically disposed header section adapt-

ed to be secured between the sides of said door frame contiguous to the upper end thereof, a first vertically disposed door section positioned in end to end relation with respect to the lower end of said header section and having one end pivotally connected to the latter on an axis transverse of and exteriorly of said header section for swinging movement toward and away from the exterior face of said header section, a second vertically disposed door section positioned in end to end relation with respect to the other end of said first door section and having one end pivotally connected to the latter on an axis transverse of and interiorly of said first door section for swinging movement toward and away from the interior face of said first door section, a shaft arranged in spaced parallel relation above said transverse axes and mounted on said header section for rotary movement, a pulley arranged adjacent each of the ends of said shaft and secured thereto, flexible means having one end trained about each of said pulleys in one direction and secured thereto and each having the other end secured to the other end of said second door section, another pulley spaced inwardly of each of said first named pulleys and secured to said shaft, another flexible means having one end trained about each of said last named pulleys in a direction opposite to said first named flexible means and secured thereto, each of said last named flexible means extending through said header section and having its other end secured to said first door section, and power means operatively connected to said shaft for effecting the rotary movement of the latter.
